of Delaware

Original application May 17, 1929, Serial No.
363,833. Divided and this application May 20,
1937, Serial No. 143,773

2 Claims. (Cl. 250—27)

This invention relates to electron discharge devices having a shielding or screening element, as well as to circuit connections therefor and means for energizing one or more of the elements or electrodes of such electron discharge devices from electric power supply means or source. The auxiliary grid or electrode is mounted between the anode and the control grid. The voltage difference between the cathode and the auxiliary grid may be of any desired value with reference to the voltage difference between the anode and the cathode.

In this arrangement, the shielding element acts to reduce or counter-balance the electrostatic field between the main anode and the control grid, the field being due to the interelectrode capacity of the electron discharge device. Such a device, therefore, may be used in radio work as an amplifier in which a higher voltage amplification may be secured under some conditions without the presence of oscillation.

An object of the invention is to devise a screen grid vacuum tube circuit so that the potential between the screen grid and cathode fluctuates similarly in phase to the fluctuations of potential between the anode and cathode.

Further objects of the invention will appear as the description proceeds.

The present case is a division of my earlier application Serial No. 363,833, filed May 17, 1929, issued as Patent 2,092,769, Sept. 14, 1937.

The invention is shown in the accompanying drawing, in which the single figure is a diagrammatic view of the invention.

Referring to the drawing, it will be seen that an evacuated vessel or envelope 1 encloses an equipotential or indirectly heated cathode 2, an anode 3, a control grid 4 and a screen grid 5. The screen grid is interposed between the control grid and the anode and may, if desired, have a portion 5' located beyond the anode in order to shield the anode from the control grid 4 as well as from possible external disturbances. The equipotential or indirectly heated cathode is heated in any desired manner as by means of the filament 6.

A rectifier is provided which is placed inside the evacuated enclosure. The cathode 7 of the rectifier is heated by the filament 8 and is connected through smoothing means, including a resistance 10 and condensers 11 and 12, to one end of a resistance 12'. The other end of the resistance is connected to the negative side of the condensers 11 and 12. The positive sides of the condensers are connected to opposite ends of the resistance 10. The smoothing means, consisting of

the resistance and condensers, is connected to one end of the output coil or primary 13, the other end of this primary is connected to the cathode 2 of the signal responsive device.

The screen grid or accelerating grid 5 may have any desired voltage impressed thereon by connecting it to a selected point of the resistance 12', as shown in the drawing. As shown in the drawing, the filaments 6 and 8 and the entire device, in fact, may be directly supplied from the industrial alternating or direct current mains 14. One side of the mains is connected to the anode 15 of the rectifier, the other side of the mains may be connected through a rheostat 16 to the smoothing means and to one side of the series-connected filaments 6 and 8, the other side of the series-connected filaments being connected to the anode 15 of the rectifier and, consequently, completing the circuit back to the other main. The indirectly heated cathode 7 of the rectifier is connected to one side of the smoothing means and the smoothing means is connected to the anode 3 of the signal responsive device. The resistance 12' is bridged around the smoothing means and a selected point thereof is connected to the screen grid 5. The input circuit may include the secondary 17 of the input transformer, whose ends are connected to the equipotential or indirectly heated cathode 2 of the signal responsive device and to the control grid 4. The cathode 2 of the signal responsive device is connected to the output circuit, for instance, the primary 13 of an output transformer. The other end of this output transformer is connected to the smoothing means and thus the circuit is completed. As shown in the drawing, the screen grid tube and the circuits therefor are well adapted to be energized from a source of either alternating current or direct current such as the city mains 14. Also, as shown in the drawing, the filament or cathode heating means 8 of the rectifier and the filament or heater 6 of the screen grid device are arranged in the same circuit with the resistance 16 and supplied in series from the alternating or direct current mains 14.

It will be seen that the anode 3, as shown diagrammatically, is enclosed or surrounded by the electrostatic shielding or screening means 5 and 5'. In other words, this anode 3 may be located, as shown diagrammatically, between a plurality of screening or shielding portions, members or elements which may be similar or dissimilar in structure, and which are placed opposite to a plurality of surfaces or sides of the anode 3 and spaced therefrom. Therefore these shielding or

screening means are adapted to substantially intercept the electrostatic lines of force extending between the inner and outer sides or surfaces of the anode and some one or more of the elements of the device, such as the control electrode or grid 4, whereby the capacity between the anode 3 and the control electrode 4 or the capacitive coupling thereof is materially reduced or practically obviated.

10 It will be seen that means, given for illustrative purposes, are provided in the system which enable the screen grid of the tube to be supplied at any suitable positive potential varying from that supplied to the anode or to the anode circuit down to the potential of the cathode, as a variable connection has been illustrated. Obviously, different types of screen grid tubes required different voltages for the screen grid, but this invention provides any desired voltage for the needs of any particular type of tube to thereby secure the maximum efficiency.

15 It is to be appreciated that the smoothing means may be located outside of the base of the tube, if desired, and may have any form, a number of forms being disclosed in my original application previously referred to herein.

20 It is to be understood that the equipotential or indirectly heated cathodes are preferably coated or otherwise associated, with a thermionic oxide 30 so that they will emit electrons at a relatively low temperature, although, obviously, the spirit of the invention will not be departed from if plain uncoated equipotential or indirectly heated cathodes are employed.

25 It is to be noted, also, that the alternating current source is intended primarily to be the industrial alternating current supply mains, whether connected to the tube through a transformer or any other device or whether connected 35 directly to the tube. It will be noted that provision has been made in this invention for a complete and entire elimination of all batteries if so desired and that the entire device may be energized from alternating current with the assurance that a stable, satisfactory and reliable 40 condition of operation will be maintained at all times.

50 While the electron discharge device described above is suitable for alternating current operation, nevertheless, it is well understood that the invention is not to be limited to the use of alternating current for wholly or partially ener-

gizing this device, but that the invention will operate also with direct or fluctuating current as well as with alternating current.

In my invention the screen grid is so connected to the load circuit that the potential between the screen grid and the cathode fluctuates similarly in phase to the fluctuations of potential between the anode and cathode. That is, the screen grid voltage has an alternating component of similar phase to the alternating component of the anode voltage.

Having described my invention, what I claim is:

1. The combination of an electron discharge device comprising a cathode, a control grid, an 15 anode and a second grid for preventing the anode potentials from appreciably affecting the anode current over a wide range of anode potentials, means for applying a positive voltage to the anode in respect to the cathode, means for applying a lesser positive voltage to the second grid 20 in respect to the cathode, a load circuit connected between the cathode and anode, an input circuit connected between the control grid and the cathode to control the space current flowing between said cathode and anode, one of said grids having connections to the load circuit for impressing between it and the cathode, fluctuations of potential similar in phase to the fluctuations of potential between the anode and cathode produced by fluctuations of the current 25 flowing through said load circuit.

2. The combination of an electron discharge device comprising a cathode, a control grid, an 30 anode and a second grid for preventing the anode potentials from appreciably affecting the anode current over a wide range of anode potentials, means for applying a positive voltage to the anode in respect to the cathode, means for applying a less positive voltage to the second grid 35 in respect to the cathode, a load circuit connected between the cathode and anode, an input circuit connected between the control grid and the cathode to control the space current flowing between said cathode and anode, said second grid having connections to the load circuit for impressing fluctuations of potential between it and the cathode which are similar in phase to the fluctuations of potential between the anode and cathode, produced by fluctuations of the current 40 flowing through said load circuit.

ARISTOTE MAVROGENIS.
